UNITED STATES PATENT OFFICE.

EARLL R. STONE, OF WILKINSBURG, PENNSYLVANIA, ASSIGNOR TO WESTINGHOUSE ELECTRIC & MANUFACTURING CO., A CORPORATION OF PENNSYLVANIA.

STOKER.

Application filed November 8, 1919. Serial No. 336,668.

To all whom it may concern:

Be it known that I, EARLL R. STONE, a citizen of the United States, and a resident of Wilkinsburg, in the county of Allegheny and State of Pennsylvania, have made a new and useful Invention in a Stoker, of which the following is a specification.

This invention relates to stokers and particularly to a new and improved fuel feeding apparatus for stokers.

The capacity of some stokers, particularly those of the chain grate type, is limited by the relatively slow rate of combustion of the fuel. In the ordinary constructions ignition takes place at the surface and progresses downward into the fuel bed as the fuel passes through the furnace. This action is opposed by the draft or blast of relatively cool air coming up through the relatively cool fuel bed and consequently combustion is retarded and the capacity of the stoker limited.

An object of my invention is to produce a new and improved fuel feeding arrangement for stokers whereby the rate of combustion of the fuel may be accelerated.

A further object is to produce a new and improved stoker in which combustion occurs on the surface of the bed of fuel in one part of the stoker and within the bed of fuel in another part of the stoker.

A further object is to produce a new and improved chain grate stoker having a greater fuel burning capacity for a given grate area than other chain grate stokers now in use and known to me.

A further object is to produce a new and improved method of feeding fuel into a furnace whereby the sifting of fine fuel through the grate is substantially eliminated and a high rate of combustion obtained.

These and other objects which will be made apparent throughout the further description of my invention are obtained by means of apparatus embodying the features herein described and illustrated in the drawing accompanying and forming a part hereof.

The drawing is a diagrammatic sectional view of a stoker embodying my invention.

In the drawing I have illustrated a stoker 5 of the chain grate type as installed under a boiler 6. As shown, the stoker 5 is mounted on wheels 7 and rails 8 in such a manner that it may be moved into and out of opera-

tive relation with the boiler 6. I have illustrated the stoker in operative position relative to the boiler 6 and spaced from a bridge wall 9, so as to form an ash discharge opening 10 at the rear end of the stoker. In the construction illustrated the stoker 7 is of the Dutch oven type, that is, the stoker and combustion space 11 extend out in front of the boiler 6 a considerable distance.

As shown, the front portion of the stoker is covered by fire brick arches 12^a and 13^a, the rear arch 13^a being higher than the front arch 12^a. With this arrangement the cross-sectional area of the combustion space 11 increases from the front end of the stoker toward the rear or boiler end, and therefore provides ample space for the cumulative volume of gases rising from the fuel bed. As illustrated, the stoker 5 comprises an endless chain grate 12 which is supported on a frame 13 and on suitable sprocket wheels 14 and 15 located at opposite ends of the frame. Power for operating the grate is delivered to the front sprocket wheel 14 by means of the worm 16 and the gear 17, this construction being familiar to those skilled in the art and requiring no further description.

At the front end of the grate 12 I have shown a hopper 18 for delivering fuel to the grate. As illustrated, a gate 19 is provided and may be controlled or adjusted in any suitable manner, for example, by means of a crank 20 and suitable gearing 21, such as is frequently employed in ordinary chain grate stoker construction. As illustrated, fuel is delivered to the hopper 18 by means of an inclined chute or spout 22. In the bottom of the spout 22 and at some distance from the hopper 18 I have shown a screen 23 by means of which the fine fuel is sifted out of the mass of fuel coming down the spout 22.

The fine fuel which passes through the screen 23 is collected and stored in an auxiliary hopper 24 which, as shown, is located above the fire brick arch 12^a. As illustrated, the lower part of the hopper 24 terminates in a passage 25 located between the front and rear fire brick arches 12^a and 13^a and extending across the chain grate 12 and opening into the combustion space 11. An agitator or fuel feeding device 26 is shown in the lower part of the hopper 24 for feeding the fine fuel into the passage 25. The fuel fed into the passage 25 drops on top of

the fuel carried into the furnace from the front or main hopper 18 by the chain grate.

The feeding device illustrated is adapted to be driven by means of sprocket wheels 27 5 and a suitable chain 28, the lower sprocket wheel 27 being geared to the main sprocket wheel of the chain grate by means of suitable gears 29. Obviously, the speed of the feeding device will bear a definite relation 10 to the speed of the chain grate 12 and, if desired, the gears 29 may be so arranged that this relation of speeds may be varied to suit different operating conditions.

Stokers such as that illustrated may be 15 operated either with natural draft or with forced or induced draft. In the drawing, I have illustrated a forced draft arrangement comprising air boxes 30 located immediately below the upper portion of the grate 12 20 and adapted to deliver air under pressure upwards through the grate and the fuel bed. The air may be delivered at different pressures from different air boxes so that the blast may be adjusted to suit the local thickness 25 of the fuel bed. For example, the intermediate air boxes 30 may deliver air at a greater pressure or velocity than the end boxes, the fuel bed being thicker on the center portion of the grate than at either end 30 and therefore offers greater resistance to the flow of air.

In operation, the coarser fuel is delivered 35 to the grate 12 by the spout 22 and the hopper 18. It is ignited as it passes from under the gate 19 into the combustion space 11. The finer fuel is fed on top of the coarse fuel by means of the feeding device 26 as the grate carries coarse fuel under the passage 25. The fire is then in the middle portion of 40 the fuel bed and combustion proceeds at a rapid rate.

A separate supply of fuel may be fed to each of the two hoppers 18 and 24, but coarse fuel is preferably delivered to the hopper 45 18, as it is more free burning than fine fuel and does not tend to sift through the grate. The finer fuel is preferably fed on top of the coarse fuel after the latter is well ignited, and is thereby effectively prevented 50 from sifting. The arrangement illustrated ensures a fine distribution of the fuel fed on to the grate so that the tendency of the blast to form pockets in the fuel bed is substantially eliminated.

55 While I have described and illustrated but one embodiment of my invention, it will be apparent to those skilled in the art that various changes, modifications, additions and omissions may be made in the apparatus de-

scribed and illustrated without departing 60 from the spirit and scope of the invention as set forth by the appended claims.

What I claim is:

1. In a furnace having a progressive feed grate, the combination of an inclined fuel 65 chute, a hopper associated therewith at an elevated position, a portion of the chute being perforated to form a screen adapted to deliver finer fuel to said elevated hopper, a second hopper at a lower level and in front 70 of the elevated hopper and positioned to receive coarser fuel from the lower end of the chute and means associated with each hopper to distribute the fuel fed by the chute to non-contiguous portions of the grate. 75

2. In a furnace having a progressive feed grate, the combination of a hopper at an elevated position and adapted to deliver fuel to an intermediate portion of the furnace grate, a second hopper at a lower level and in front 80 of the elevated hopper and adapted to deliver fuel to an end portion of the furnace grate, an inclined fuel chute adapted to supply fuel to the hoppers, and means provided in said chute to deliver fine fuel to the 85 elevated hopper and coarse fuel to the lower hopper.

3. In a furnace in which the fuel is fed at non-contiguous places along a progressive feed grate, the combination of an elevated 90 hopper, a second hopper disposed in front of and below the elevated hopper, an inclined fuel chute adapted to supply fuel to each hopper, a screen in said chute so disposed 95 with relation to the elevated hopper as to deliver fine fuel to the elevated hopper, and means associated with each hopper to control the rate of distribution of fuel onto the said non-contiguous portions of the grate.

4. In a furnace having a progressive feed 100 grate in which fuel is fed on the grate at non-contiguous places, the combination of an elevated hopper, a second hopper disposed in front of and below the elevated hopper, an inclined fuel chute supported by the elevated hopper and extending into the second hopper, means associated with the chute and the elevated hopper for separating the finer from the coarser fuel and delivering the finer fuel to the elevated hopper, and means 110 associated with each hopper to control the rate of distribution of fuel onto the non-contiguous portions of the furnace grate.

In testimony whereof, I have hereunto 115 subscribed my name this seventh day of November, 1919.

EARLL R. STONE.
